UNITED STATES PATENT OFFICE.

FRANK E. CAIN, OF DETROIT, MICHIGAN.

ENGINE.

1,075,662.

Specification of Letters Patent. Patented Oct. 14, 1913.

Application filed July 5, 1912. Serial No. 707,686.

To all whom it may concern:

Be it known that I, FRANK E. CAIN, a citizen of the United States of America, residing at Detroit, in the county of Wayne 5 and State of Michigan, have invented certain new and useful Improvements in Engines, of which the following is a specification, reference being had therein to the accompanying drawings.

10 This invention relates to improvements in internal combustion engines and more particularly to a construction and arrangement of a cylindrical valve for multiple cylinder engines of the vertical type.

15 The object of the invention is to so construct and arrange the valve that one inlet and one exhaust port will serve two adjacent cylinders and leakage past the valve and the ports will be prevented thus obviating the loss of compression.

20 A further object of the invention is to so construct the valve that it may be efficiently cooled by a circulation of water therethrough and to provide certain other new and useful features in the construction and arrangement of parts all as hereinafter more fully described.

25 To these ends the invention consists in the matters hereinafter set forth and more particularly pointed out in the claims reference being had to the accompanying drawing in which—

30 Figure 1 is a longitudinal vertical section through the upper end of the cylinders of an engine embodying the invention; Fig. 2 is a transverse vertical section of the same upon the line $x-x$ of Fig. 1; Fig. 3 is a side elevation of the valve detached; Fig. 4 is a transverse section of the same on the line 40 $y-y$; Figs. 5 and 6 are views of a packing ring detached.

35 In the drawing the several cylinders 1 are shown as cast *en bloc* but it will be understood that they may be as well cast in pairs, 45 and the upper end or head portion 2 of the cylinders is bored transversely of the cylinders and longitudinally of the head across their upper ends to form a cylindrical seat 3 for a cylindrically shaped valve member 4. The upper ends of the cylinders or head 50 is formed in the usual manner with a water space 5 through which water may be circulated to cool the parts and the valve member 4 is forced Fallon throughout its length

and provided with tubular extensions 6 and 7 at its ends into which water passages 8 and 9 formed in caps 10 and 11 respectively, open at one end, the opposite ends of said passages being connected with the water space 5 to permit the water to circulate 60 freely through the valve member. The tubular extensions 6 and 7 engage removable bearings 12 and 13 respectively, and to make a water tight joint within the extensions tubular bosses 14 are formed on the caps 10 65 and 11 to project into the tubular extensions, and a packing gland 15 is provided in each extension to engage the inner end of the tubular bosses, said gland being held in place by a suitable tie bolt 16 extending outward through an opening in the cap.

70 Each cylinder is formed with a port 17 in its upper end opening through the lower side of the valve seat 3 and the head is formed with an inlet port 18 and an exhaust port 19 75 opening through one side of the valve seat at a point midway between two adjacent cylinders so that each inlet and exhaust port may serve to admit charges to two cylinders and allow the escape of the products of combustion from a pair of cylinders. The valve member 4 is formed with an annular port channel 20 opposite each of the ports 17 leading into the cylinders and these port channels are formed with lateral extensions 80 21 reaching longitudinally of the valve to a point beyond the adjacent inlet and exhaust ports which are located at one side of the cylinder while the port 17 and its corresponding port channel 20 is located in the 90 central vertical plane of the cylinder. During the rotation of the valve, the lateral extension of each port channel is brought alternately opposite the inlet and exhaust ports thus uncovering said ports and permitting combustible charges to enter the cylinder through the lateral extension and annular port channel and permitting the exhaust from the cylinder to escape therefrom in timed relation to the movement of the pistons 22 through the annular channel and its lateral extension to the exhaust port. The port channel which controls the inlet and exhaust from one cylinder of each pair has its lateral extension at one side of the valve 95 100 and the port channel which controls the inlet and exhaust from the other cylinder of the pair has its lateral extension at the dia-

metrically opposite side of the valve, said extensions extending laterally from their channels in opposite directions and overlapping each other at their adjacent ends in their path of travel substantially the width of the ports.

The cylindrical portions 23 at the ends of the valve fit loosely within the valve seat to turn freely therein and are provided with 10 annular packing rings 24 fitting within grooves in said portions to make a tight joint and prevent leakage longitudinally of the valve in one direction from the adjacent annular port channel. The cylindrical portion 25 of the valve which lies between the pairs of cylinders, is also provided with annular packing rings 24 to make a tight joint at one side of the adjacent annular port channels. To prevent leakage from the 15 port channels and their lateral extensions longitudinally of the valve, said valve is formed with a groove 26 in its face extending along adjacent to one side of which channel and adjacent to the edge of the lateral extension thereof and within each of these 20 channels is a split packing ring 27, shown in Figs. 5 and 6, having a straight portion to fit within the annular portion of the groove and a laterally curved and extended portion 25 to fit within that portion of the groove which lies adjacent to the edge of the channel extension. When the valve is turned with one of the extensions of the port channel opposite one of the ports, the ring 27 lies against 30 the wall of the valve seat around the port and thus prevents any leakage past the valve from one port to the other or along the valve seat into the adjacent port channel.

Openings are provided in the head portion 40 2 to receive suitable spark plugs 28, said openings being located directly opposite the port channels in the valve which channels together with their lateral extensions form a part of the compression and firing chamber of the cylinder and as these channels as 45 well as the upper end of the cylinder contain the explosive charges at the time of firing, the force of the explosion is substantially equal in all directions upon the valve.

In this construction the valve may be 50 quickly and easily removed for the replacement or repair of its packing rings by removing one of the caps 11 or 12 which close the ends of the cylindrical seat or bore 3 for the valve and as the valve is formed hollow throughout its length and connected with the water space surrounding the cylinders and head, the valve is efficiently cooled and all liability of its becoming expanded within 55 its port to such an extent as to prevent its turning freely therein is obviated.

Obviously, changes may be made in the form and construction of the valve and in its arrangement and position in relation to 60 the cylinders without departing from the

spirit of my invention and I do not care to limit myself to the particular form and construction shown.

Having thus fully described my invention what I claim is:—

1. In an internal combustion engine, the combination of a cylinder having a portion provided with a bore forming a seat for a valve and formed with an inlet and an exhaust passage opening into said bore, and a 70 valve member in said bore provided with an annular port-channel in constant communication with the cylinder and having a lateral extension adapted to register with said inlet and exhaust passages.

2. In an internal combustion engine, the combination of a pair of cylinders having a portion provided with a valve seat and an inlet and an exhaust passage for the two cylinders opening through said seat, a valve member engaging said seat and formed with an annular channel for each cylinder in constant communication therewith, each channel being formed with a lateral extension to register with said passages.

3. In an internal combustion engine, the combination of a cylinder having a portion provided with a bore forming a seat for a valve and formed with an inlet and an exhaust passage opening into said bore, and a 90 valve member in said bore provided with an annular port-channel in constant communication with the cylinder and having a lateral extension adapted to register with said inlet and exhaust passages, said member being 100 also formed with grooves adjacent to the edges of said channel and lateral extension thereof, and packing rings in said grooves one of which is formed with an off-set portion to fit within the groove adjacent to the 105 edge of the lateral extension of the channel.

4. In an internal combustion engine, the combination of a pair of cylinders having a portion provided with a valve seat, and an exhaust passage for the two cylinders opening through said seat, a valve member engaging said seat and formed with an annular channel for each cylinder in constant communication therewith, each channel being formed with a lateral extension to register with said passages, said extensions being positioned at diametrically opposite sides of the valve and overlapping each other in their path of travel, and said valve being provided with grooves adjacent to the 115 edges of said channels and the extensions thereof, and packing rings having off-set portions to engage said grooves.

5. In an internal combustion engine, the combination of a cylinder having a water 125 jacket and a head provided with a bore forming a seat for a valve and also formed with inlet and exhaust passages opening into the bore, a hollow cylindrical valve within the bore having an annular port-channel in 130

communication with the upper end of the cylinder said channel being formed with a lateral extension adapted to register with the inlet and exhaust passages when the 5 valve is turned, and members at the ends of the valve provided with passages connecting the interior of the valve at its ends with the water jacket.

6. In an internal combustion engine, the 10 combination of a plurality of cylinders, a head portion for said cylinders formed with a bore extending transversely of the cylinders across their upper ends and communicating therewith, said head being also 15 formed with an inlet and an exhaust passage for each pair of cylinders, a valve member in said bore formed hollow throughout its length and having annular port-channels in constant communication with the cylinders, each channel being formed with a hollow extension to register with the inlet and exhaust passages, removable bearings for the ends of the valve member, and caps closing the ends of the valve member and 20 formed with passages for conducting water thereto to circulate therethrough.

7. In an internal combustion engine, the 25 combination of a plurality of vertical cylinders provided with water jackets, a head 30 on the cylinders formed with a bore forming a valve seat extending horizontally across the upper ends of all of the cylinders with a passage opening into the upper

end of each cylinder and into the bore and with an inlet and exhaust passage located 35 midway between the cylinders of each pair of cylinders and opening into the bore, a hollow cylindrical valve member in said bore formed with annular port-channels opposite the passages opening into the upper 40 ends of the cylinders, said channels being formed with lateral extensions to register with the inlet and exhaust passages when the valve is turned and the valve being provided with grooves along the edges of each 45 port-channel and its lateral extension, the lateral extensions of the port-channels for adjacent cylinders being extended laterally from the channels in opposite directions and at opposite sides of the valve, packing rings 50 in said grooves, certain of said rings being formed with off-set portions to engage the groove extending around the lateral extensions of the port-channels, and caps covering the ends of the valve member and provided with passages opening into the open 55 end of the valve member at one end and communicating at their opposite ends with the water jacket.

In testimony whereof I affix my signature in presence of two witnesses.

FRANK E. CAIN.
